1869. BOSTON, MASS.

United States Patent Office.

GEORGE A. SEAVER, OF NEW YORK, N. Y.

Design No. 3,752, dated November 16, 1869.

DESIGN FOR A COTTON-KNIFE.

The Schedule referred to in these Letters Patent and making part of the same.

I, GEORGE A. SEAVER, of New York, in the county and State of New York, have invented and produced a new and original Design for a Cotton-Knife, of which the following is a specification.

The nature of my design is fully represented in the accompanying drawing, to which reference is made.

Claim.

I claim, as my invention, the design for a knife, as shown.

Witnesses:

DANL. J. DAY,
W. K. HALL.
